(57) **CLAIM**

The ornamental design for a nameplate, as shown and described.

DESCRIPTION

FIG. 1 is a front perspective view of a nameplate showing our new design;

FIG. 2 is a front view thereof;

FIG. 3 is a top view thereof;

FIG. 4 is a right side view thereof;

FIG. 5 is a left side view thereof;

FIG. 6 is a rear view thereof;

FIG. 7 is a bottom view thereof; and,

FIG. 8 is a cross sectional view thereof, taken along line 8-8 in FIG. 2.

The broken lines shown in the drawings illustrate portions of the nameplate that form no part of the claimed design.

1 Claim, 8 Drawing Sheets
